UNITED STATES PATENT OFFICE.

JOHN L. GOOD, OF HORTON, KANSAS.

AUXILIARY BLOW-OFF AND WATER-INLET FOR LOCOMOTIVE-BOILERS.

1,289,441.

Specification of Letters Patent. Patented Dec. 31, 1918.

Application filed October 18, 1917. Serial No. 197,315.

To all whom it may concern:

Be it known that I, JOHN L. GOOD, a citizen of the United States, and a resident of Horton, in the county of Brown and State 5 of Kansas, have invented certain new and useful Improvements in Auxiliary Blow-Offs and Water-Inlets for Locomotive-Boilers, of which the following is a specification.

The present invention relates to an attachment for locomotives and the like, and has for an object to provide an attachment 10 for facilitating the exhaust of steam and smoke from the locomotive when stationed in round-houses and the like.

15 It is the present practice to run locomotives into round-houses beneath smoke-jacks or flues which conduct smoke and gases from the stack of the locomotive through the roof of the roundhouse to prevent accumulation of smoke and gases 20 therein.

It is also the present practice, when it is desired to exhaust all steam from the boiler of the locomotive, to attach a length of pipe 25 to the steam chest or other convenient place of attachment and open the throttle of the locomotive for exhausting steam from the boiler through the various devices connected to the locomotive and out through the pipe 30 to the exterior of the roundhouse. Considerable time is required in attaching this pipe to the locomotive and furthermore steam is permitted to escape through the various joints and connections uniting the parts of 35 the locomotive through which the exhausting steam is conducted. This exhausting steam soon fills the roundhouse and prevents access of workmen to the various parts of the locomotive to repair the same. Furthermore, 40 the attached pipe obstructs the passages about the locomotive and materially interferes with the carrying on of work in the roundhouse. Further, the smoke and gases passing upwardly through the stack of 45 the locomotive do not always pass up through the jack or exhaust pipe in the roof of the roundhouse and thus quickly fill the roundhouse and interfere with the carrying on of the work therein.

50 It is the purpose of the present invention to provide a relatively simply constructed and applied device for a locomotive to take care of these two conditions and overcome the disadvantages found.

55 Various other objects and advantages of this invention will be in part described, and

in part understood, from the following detailed description of the present preferred embodiment, the same being illustrated in the accompanying drawing wherein—

Figure 1 is a side elevation of the front end of a locomotive arranged beneath a smoke-jack and being partly broken away, showing the attachment of this invention applied to the locomotive.

Fig. 2 is a side elevation, partly in section, of the steam and smoke exhausting device of this invention, the view being enlarged.

Fig. 3 is a further enlarged sectional view 70 through the upper end of the device of this invention, showing the removable closure cap which may be employed.

Referring to this drawing, A designates the boiler of a locomotive, B the smoke 75 box thereof upwardly from which leads the smoke-stack C, and D designates a smoke-jack or exhaust pipe such as is usually employed in the roofs of round-houses and the like for conducting smoke and gases directly 80 from the stack C through the roof of the round-house.

The device of this invention comprises a pipe which is composed of a connecting section 10 and an exhaust section 11. As shown 85 in Fig. 2, the connecting section 10 preferably comprises a pair of nipples secured to the opposite ends of the interposed valve 12, the valve controlling the passage of steam or other fluid through the connecting section. The lower end of the section 10 is adapted for attachment directly through the upper wall of the boiler A, adjacent the front tube sheet 20 thereof, to receive steam directly from the boiler adjacent the stack 95 seat, and also to deliver water or the like, directly into the boiler. The valve 12 is provided with a handle 13 which preferably projects forwardly from the connecting section 10, and which is within easy access 100 of a workman when it is desired to open the valve.

The upper end of the connecting section 10 is secured to one end of a T-coupling 14 the upper end of which is closed by a removable plug 15 and the shank or lateral portion thereof having connection with the exhaust section 11 through pipe 16 and elbow 17. The exhausting section 11 is adapted to lie close against the rear side of the 110 stack C, and may be held in such position by means of a strap or band 18 surrounding

the stack C and engaging the exhausting section 11. The upper end of the section 11 terminates preferably slightly below the plane of the upper open end of the stack C and is arranged in position to provide an unobstructed passage of steam upwardly from the open end of the exhausting section 11. The exhausting section 11 is so located to dispose the exhausting section as well as the stack C beneath the smoke-jack D when the locomotive is brought to its usual position in the roundhouse.

After an engine is brought into the roundhouse beneath the jack D, and it is found that the smoke and gases do not pass freely through the jack D, it is only necessary to open the valve 12 to the desired extent for projecting steam upwardly into the jack D and thus creating a draft which readily carries off all the smoke and gases.

When it is desired to blow off the boiler it is unnecessary to employ the usual exhaust pipe and connect it in the usual manner to the steam chest or other part of the locomotive. It is only necessary to open the valve 12 to the desired extent so as to allow the steam to blow off directly from the boiler and up through the jack D. In this manner it is unnecessary to open the throttle and thus the steam is not permitted to escape through the various connections, the cylinders, packing boxes and the like, as is usual. The roundhouse is thus kept free from steam as the latter is directed upwardly into the jack D through the exhausting section 11 of the device. The use of this device does not only maintain the atmosphere within the roundhouse clear and in a healthy condition, but it also reduces the length of time required for exhausting a boiler as considerable time is necessary for connecting the usual exhaust pipe and adjusting it to a window or the like through which the steam may be exhausted.

If desired, the exhausting section 11 may be provided with external screw-threads at its upper end for the reception of a closure trap 19, the trap being employed when it is desired to press the joint of the pipe, and when it is desired to introduce water into the boiler through the T-coupling 14 by the removal of the plug 15.

The plug 15 being located at the top of the connecting section 10 admits of the ready removal of the plug when the boiler is under pressure as the valve doors may be closed and all danger of burning the workmen by exhausting steam is thus overcome. When the water connection is made with the nipples 14, the valve 12 may then be opened and the water under suitable pressure may be

projected into the boiler A. It is therefore unnecessary to remove the plugs located within the cab as is now the general practice. 65

By the use of the present invention a first draft is created upwardly through the jack D for the removal of smoke and other gases from the stack C. The device of this invention also facilitates the exhaust of steam 70 from the boiler without danger to the workmen in the roundhouse and also without impeding the progress of the work therein. The use of the present invention further facilitates the filling of the boiler with water 75 under conditions which are improved from the general present practice.

It is of course understood that various changes and modifications may be made in the details of construction of the above specifically described embodiment of this invention without departing from the spirit thereof to adapt the device to various conditions met with in locomotive construction, such changes and modifications being restricted only by the scope of the following claims: 80

What is claimed is:

1. The combination with a locomotive having the usual boiler and a smoke stack 90 adapted to be centered under a smoke outlet when the locomotive is in a round house or the like, of a blow-off device opening into the upper portion of the boiler adjacent the front tube sheet thereof and opening at its other end in proximity to the upper portion of the stack for directly discharging steam through the smoke outlet from the top of the boiler to the exclusion of the throttle and other parts of the locomotive, and a controlling valve in the device adapted to be manipulated for blowing off steam from the boiler without the use of temporary fittings. 95

2. The combination with a locomotive 105 having the usual boiler and a smoke stack adapted to be centered under a smoke outlet when the locomotive is in a round house or the like, of a connecting pipe section tapped into the top of the boiler near the smoke 110 stack and rising directly from the boiler, a T-coupling connected by one arm to the upper end of the connecting pipe section, a removable plug in the other arm of the T-coupling adapted to be removed for introducing water into the boiler, an exhausting pipe section extending upwardly against one side of the smoke stack, a pipe section leading from the shank of the coupling to the exhausting section, and a controlling valve 115 interposed in the connecting pipe section below the T-coupling. 120

JOHN L. GOOD.
